Application June 27, 1938, Serial No. 216,081

10 Claims. (Cl. 155—179)

This invention relates to upholstery construction, and is particularly directed to upholstered chairs or sofas provided with a one piece webbing and improved means to support the webbing.

An object of this invention is to provide a highly improved strong and durable support for a one piece webbing, which shall be relatively inexpensive to manufacture, easy to apply, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a top plan view of a chair frame provided with webbing supporting means embodying the invention;

Fig. 2 is a cross-sectional view taken on line 2—2 of Fig. 1;

Fig. 3 is a bottom plan view taken on line 3—3 of Fig. 2;

Fig. 4 is a view similar to Fig. 1, but illustrating a modified construction;

Fig. 5 is a cross-sectional view taken on line 5—5 of Fig. 4;

Fig. 6 is a perspective view of one of the straps for mounting the coil tension springs;

Fig. 7 is a perspective view of one of the brackets shown in Figs. 4 and 5; and

Fig. 8 is an elevational, cross-sectional view through a portion of a seat provided with webbing support embodying the invention, and illustrating a modified construction.

Referring now in detail to the drawings, 10 designates an upholstered chair provided with web supporting means embodying the invention. The chair 10 comprises a frame 11 having a front wall 12, a rear wall 13, side walls 14, and legs 15. The chair may be provided with a back 16 of any suitable construction.

Attached to the bottom edges of the frame walls 12, 13 and 14, is a one-piece flexible webbing 20, made of burlap or any other suitable material. The webbing 20 is attached at substantially its entire margin to the bottom edges of the walls 12, 13 and 14.

Mounted on the webbing 20 are a plurality of rows of foundation springs 21, interconnected and

attached to the frame 11, by the usual tie cords 23. The foundation springs may be covered in accordance with usual upholstery practice.

Improved means is provided to aid in supporting weight imposed upon the foundation springs, to prevent sagging of the webbing and for relieving tension from the fastening means which attach the webbing to the frame, so as to prevent the attaching means from being torn away from the frame. To this end, there is provided a member 25 preferably made of a single piece of round wire stock and contacting the underside of the webbing and spaced from the walls 12, 13 and 14 of the frame. Said member 25 comprises a pair of parallel portions 26, parallel to the side walls 14 of the frame, and a portion 27 parallel to the rear wall 13. Said portion 27 is preferably located closer to the rear wall 13 than to the front wall 12 of the frame. Said portions 26 of the member 25 are each formed, adjacent the ends thereof, with a pair of upwardly extending offset portions 29 and 30 piercing the webbing. Interposed between said portions 26 and the webbing 20, are washers 29a and 30a, receiving the offset portions 29 and 30 respectively. The distance between the offset portions 29 and the front wall 12 is preferably substantially equal to the distance between offset portions 30 and the rear wall 13 of the frame.

Means is provided for yieldingly interconnecting the offset portions 29 and 30 with the front and rear walls of the frame. To this end, there is attached to each of the front and rear walls of the frame, a pair of similar straps 32, aligned with portions 26 of member 25. Each strap is preferably made from a single piece of elongated, flat, thin, easily bendable metal. The strap members 32 may be readily bent to the shape shown in the drawings.

As shown in the drawings, each strap member 32 comprises a vertical portion 34 contacting the outer surface of the frame wall, a horizontal portion 35 extending from the front portion 34 and contacting the top edge of the frame wall, 45 and a portion 36 extending from said top portion and inclined downwardly toward the adjacent offset portion 29 or 30. The strap member 32 may be formed with a plurality of spaced openings 38 to receive nails or other fastening members 40, driven into the outer and top surface of the frame wall to attach the strap to the wall. The inner end of portion 36 of each strap member is formed with an opening 42. Said straps are interconnected to the adjacent offset portions by coil tension springs 45. One end of

each spring engages one of the offsets, and the other end engages within the opening 42 of the strap 32.

It will now be understood that the webbing is yieldingly supported to aid in supporting weight imposed on the foundation springs, and to prevent sagging of the webbing, and to prevent tearing away of the fastening means which attach the webbing to the frame.

The strap members 32 may be attached to the frame walls in various adjusted positions depending upon the depth of the frame. The fastening nails 49 may be driven through any of the openings 33, and the strap member may be bent into the shape shown in Figs. 1, 2 and 6 of the drawings, producing portions 36 of greater or less length to suit the size of the frame.

In Figs. 4, 5 and 7 there is illustrated a modified form of the invention. In said figures, the webbing 20 is supported by a member 59, likewise made of a single piece of round wire stock. Said member 59 has parallel portions 51 contacting the underside of the webbing and disposed parallel to the side walls 14 of the frame. Portions 51 are interconnected by a portion 52, parallel and adjacent to the rear wall 13 of the frame. Said portions 51 are each formed, adjacent the portion 52, with an upwardly extending offset portion 53 piercing the webbing. A washer 54 received on the offset 53 of each portion 51, is interposed between the webbing and said portion 51 of member 59.

Extending upwardly from the forward ends of portions 51 are upwardly inclined integral portions 56, connected at their upper ends to brackets 57 attached to the upper edges of the front wall 12. The upper ends of portions 56 may merely be looped through the brackets 57 to make the connection.

In Fig. 8 there is shown another modified form of the invention. In Fig. 8, the seat frame is provided with a one piece webbing fixed to the underedge of the frame. For the purpose of supporting the webbing, there is provided a member 61, similar to the member 59, shown in Figs. 4 and 5, similarly supported at one end by a pair of springs 45. The side portions of the member 61, however, extend substantially to the front wall 12, being provided with upwardly extending portions 61a piercing the webbing adjacent the front wall.

Attached to the front edge of the front wall 12, are a pair of spaced parallel brackets 63 having portions 63a disposed beneath the webbing and extending inwardly of the front wall and formed with openings to receive the portions 61a of the member 61. The brackets 63 may be attached to the frame by nails 67.

Attached to the upper edge of the front wall, are a pair of brackets 64 fixed to said wall by nails 66, and having portions 65 extending inwardly of said front wall and formed with openings to receive the upper ends of portions 61a which are looped downwardly, as at 62.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. In upholstery construction, a frame having front, rear and side walls, a one piece flexible webbing attached at the margin thereof to the underedges of said frame walls, foundation springs on said webbing, and means for supporting said webbing comprising three sided U-shaped member made of a single piece of wire and having parallel portions contacting the underside of the webbing and disposed parallel to the side walls of the frame, and a portion interconnecting said parallel portions and disposed parallel to the rear wall of the frame, said parallel portions having upwardly extending offset portions piercing the webbing, and resilient means interconnecting said offset portions with the upper portions of the rear frame walls, and disposed in parallel planes passing through said parallel portions, and perpendicular to said interconnecting portion, and means to connect the free ends of said parallel portions to the front wall.

2. In upholstery construction, a frame having front, rear and side walls, a one piece flexible webbing attached at the margin thereof to the underedges of said walls, means for supporting said webbing comprising a three sided member made of a single piece of wire and having parallel portions contacting the underside of said webbing and disposed parallel to the side walls of the frame, and a portion interconnecting said parallel portions and contacting the underside of said webbing and disposed parallel to the rear wall, said parallel portions being formed adjacent the ends thereof with upwardly extending offsets piercing the webbing, a pair of strap members attached to each of the front and rear walls, and coil tension springs interconnecting said strap members with said offset portions, said strap members and said springs being disposed in parallel planes perpendicular to said interconnecting portion.

3. In upholstery construction, a frame having front, rear and side walls, a one piece flexible webbing attached at the margin thereof to the underedges of said walls, means for supporting said webbing comprising a member made of a single piece of wire and having parallel portions contacting the underside of said webbing and disposed parallel to the side walls of the frame, and a portion interconnecting said parallel portions contacting the underside of said webbing and disposed parallel to the rear wall, said parallel portions of said member being formed adjacent said interconnecting portion, with upwardly extending offsets piercing the webbing, a pair of strap members attached to the rear wall of said frame, coil tension springs interconnecting said strap members with said offset portions, a pair of brackets on the front wall of said frame, said first mentioned member having portions extending from said parallel portions piercing the webbing and inclined upwardly toward the upper edge of said front wall and engaging said brackets.

4. In upholstery construction, means for supporting the webbing of a seat frame, comprising a U-shaped member made of a single piece of wire adapted to contact the underside of the webbing and having a pair of parallel portions, and a portion interconnecting said parallel portions, said parallel portions each being formed adjacent the ends thereof with offsets, bracket members adapted to be attached to the upper

edges of the seat frame, and coil springs interconnecting said offsets with said brackets, said brackets and springs being disposed in parallel planes passing through said parallel portions and perpendicular to said interconnecting portion.

5. In upholstery construction, a frame having front, rear and side walls, webbing attached to the underedges of said frame walls, foundation springs on said webbing, and means for supporting said webbing comprising an elongated U-shaped member made of a single piece of wire and having parallel portions contacting the underside of the webbing, a portion interconnecting said parallel portions, said parallel portions having upwardly extending offset portions adjacent said interconnecting portion, piercing the webbing, spring means interconnecting said offset portions with the upper portion of a wall of said frame, said spring means being disposed in parallel planes passing through said parallel portions and perpendicular to said interconnecting portion, and means for interconnecting the outer ends of said parallel portions to an opposite wall of said frame.

6. In upholstery construction, a seat frame having front, rear and side walls, a webbing attached to the underedges of said frame walls, means for supporting said webbing, comprising a member made of a single elongated piece of wire and having parallel portions contacting the underside of said webbing, and a portion interconnecting said parallel portions and contacting the underside of said webbing, said parallel portions having offsets adjacent said interconnecting portion extending through the webbing, springs interconnecting said offsets with the upper edge of a wall of said frame, brackets on the opposite wall of said frame, the outer ends of said parallel portions being looped through said brackets.

7. In upholstery construction, a seat frame having front, rear and side walls, a one piece flexible webbing attached to the underedges of said frame walls, means for supporting said webbing, comprising a member made of a single elongated piece of wire, and having parallel portions contacting the underside of the webbing, and a portion interconnecting said parallel portions and contacting the underside of the webbing, said parallel portions having offsets adjacent said interconnecting portion, extending through the webbing, springs interconnecting said offsets with the upper edge of a wall of said frame, a pair of brackets at the upper edge of an opposite wall of said frame, and a pair of brackets at the lower edges of said opposite wall of said frame, the outer ends of said parallel

portions extending through the brackets at the lower edge of said opposite wall and extending upwardly through the webbing and adjacent the inner surface of said opposite wall, and passing through the brackets at the upper edge of said opposite wall.

8. In upholstery construction, a seat frame having a pair of parallel side walls, a front wall, and a rear wall, a one piece flexible webbing attached at substantially its entire margin to the underedges of said walls, a member beneath said webbing having parallel portions disposed parallel to the side walls of the frame, and a portion interconnecting said parallel portions disposed adjacent the rear wall of said frame, and parallel thereto, a pair of springs interconnecting said member with the rear wall of said frame, a pair of brackets at the upper edge of the front wall of the frame, and a pair of brackets at the lower edge of the front wall of said frame, the forward ends of said parallel portions passing through the brackets at the lower edge of said frame, and upwardly through the webbing, and adjacent the inner surface of said front wall, and through the brackets at the upper edge of said front wall.

9. In upholstery construction, a seat frame having front, rear and side walls, a webbing attached to the underedges of said frame walls, means for supporting said webbing, comprising a member made of a single elongated piece of wire and having parallel portions contacting the underside of said webbing, and a portion interconnecting said parallel portions and contacting the underside of said webbing, said parallel portions having offsets adjacent said interconnecting portion extending through the webbing, springs interconnecting said offsets with the upper edge of a wall of said frame, brackets on the opposite wall of said frame, the outer end of each of said parallel portions being attached to one of said brackets.

10. In upholstery construction, a seat frame, a webbing attached to the underedge of said frame, means for supporting said webbing comprising a three-sided member contacting the underside of said webbing and having a pair of parallel sides, and a third side interconnecting adjacent ends of said parallel sides, said member having portions located adjacent the junctions of the parallel sides with the third side piercing the webbing, spring means interconnecting said portions with the upper edge of a wall of said frame in alignment with the respective parallel sides of said three-sided member, and means to attach the free ends of said parallel sides to an opposite wall of said frame.

ALBERT M. BANK.
